UNITED STATES PATENT OFFICE.

GILBERT WRIGHT, OF SCHENECTADY, NEW YORK, ASSIGNOR TO GENERAL ELECTRIC COMPANY, A CORPORATION OF NEW YORK.

ELECTRICALLY-CONTROLLED DOOR-LOCK.

1,097,154.

Specification of Letters Patent.

Patented May 19, 1914.

Application filed January 31, 1913. Serial No. 745,421.

To all whom it may concern:

Be it known that I, GILBERT WRIGHT, a citizen of the United States, residing at Schenectady, county of Schenectady, State of New York, have invented certain new and useful Improvements in Electrically-Controlled Door-Locks, of which the following is a specification.

My invention relates to electrically controlled door locks and has for its object an improvement in such devices.

In hotels and the like, where electric lights and other electrical devices are employed, it has been found that frequently the occupants of the rooms will leave the same without turning off the lights or other devices which may be connected to the electric circuit and thus occasion considerable waste of electric energy.

20 The object of my invention is the construction of a simple form of electrically controlled door lock of such a nature that it is impossible for the door to be locked from the outside unless such lights or other electric devices have previously been turned off.

I accomplish the object of my invention by the use of a special form of door lock with an electro-magnetic catch of such a character that the bolt of the lock cannot be actuated 30 or shot to lock the door unless the current has been turned off from the lights or other translating devices in the room.

I am aware that a number of electric locks have been proposed of such a character that when the lock-bolt is actuated, the lights are turned off, and I am also aware that a number of electric locks have been proposed of such a character that the lock-bolt is withdrawn by means of suitable electric magnets, but I am not aware that any form of lock has been proposed similar to that which forms the object of the present invention.

For a further understanding of my invention, reference may be had to the accompanying drawing which shows, partly in section and partly diagrammatically, a form in which my invention may be carried out.

1 represents, in section, a portion of the 50 door and 2, in section, a portion of the door jamb, although it will be understood that these two members may, if desired, be transposed.

3 shows a portion of the lock which is attached to the door by means of screws 4,

and 5 shows the portion of the lock or strike plate which may be attached to the jamb by screws 6 in the manner well understood by those skilled in the art.

7 represents a portion of the lock-bolt, 60 which may be of any suitable construction and actuated in the usual manner by a key or other actuating device. When the lock-bolt 7 is shot forward, it will engage in the well known manner in a recess in the portion 65 5 of the lock, which recess has in operative relation with it a shutter 8 which is adapted in one position, such as the one shown in full lines, to prevent the entrance of the bolt into the recess. In operative relation with the 70 shutter 8 is a catch 9, which I have shown as composed of magnetic material and free to rock on a pivot 10 on an electromagnet composed of a core 11 and a coil 12 which is connected to conductors 13 of an electric 75 circuit 14 which supplies lights 15. While I have shown the circuit as supplying electric lights, it is obvious that it may not only supply these but also any other desired translating devices. A switch 16, which is 80 shown as of the usual type, is so arranged that it may turn the circuit on and off.

Fastened at one of its ends to shutter 8 is a pin 17, whose other end passes loosely through a hole 18 in catch 9. Surrounding 85 pin 17, is a spring 19, one end of which is in engagement with shutter 8 and the other end with catch 9.

The operation of my device will be as follows: When the electric circuit supplying the lamps, or other translating devices, is closed, that is the switch 16 is turned to the on position, as shown, the electromagnet will pull down the catch 9 into the position shown in full lines against the action of spring 19 and into engagement with shutter 8, preventing any motion of the shutter to the left. If an attempt be then made to actuate the lock-bolt 7 to lock the door, this will be found to be impossible, as the movement of the lock-bolt will be prevented by the shutter 8, which is restrained in its preventive position by catch 9. In order then to lock the door, it will be necessary to turn the switch 16 into the off position, in which 95 case, as the catch 9 will no longer be attracted to its closed position by the electromagnet, since the latter is now deenergized, due to the action of spring 19, it will be 100 rocked to an open position, shown by the 105 110

dotted lines, and will thus allow movement of the shutter, which, however, is kept normally, through the action of spring 19, in the position shown by the full lines in the figure, as will readily be seen. If now it is desired to actuate the lock-bolt or to lock the door, this may readily be done, the shutter 8 moving inward toward the left against the action of the spring and into the position shown in the dotted lines and thus allowing the lock-bolt to enter into engagement with the recess in portion 5 of the lock. It will thus be possible only to actuate the lock-bolt to lock the door when the lamps or other devices have been turned off and the electromagnet, therefore, deenergized, and impossible to actuate the lock-bolt when the circuit is energized.

While I have described a preferred embodiment of my invention, I do not limit myself to this embodiment but seek in the appended claims to cover all embodiments which shall be within the scope and not depart from the spirit of my invention.

What I claim as new and desire to secure by Letters Patent of the United States, is,—

1. In combination, an electric circuit, a lock comprising a lock-bolt and a strike-plate adapted to be entered by said bolt, and means for preventing such entrance when the circuit is energized.

2. In combination, an electric circuit, a lock comprising a lock-bolt, a member adapted to be engaged thereby, a movable shutter adapted in one position to prevent such engagement, and means in operative relation with the shutter to keep it in the said position when the circuit is energized.

3. In combination, an electric circuit, a lock comprising a lock-bolt, a member adapted to be engaged thereby, a movable

shutter adapted normally to allow such engagement but in one position to prevent the same, and means in operative relation with the shutter to keep it in its preventive position when the circuit is energized.

4. In combination, an electrical circuit, a lock comprising a lock-bolt, a member having a recess adapted to be engaged thereby, a movable shutter in operative relation with the bolt and the recess adapted in one position to prevent such engagement, a movable catch in operative relation with the shutter normally biased to an open position to allow movement of the shutter and in its closed position preventing such movement, and an electromagnet connected to the circuit and in operative relation with the catch adapted when energized to hold the catch in its closed position.

5. In combination, an electrical circuit, a lock comprising a lock-bolt, a member having a recess adapted to be engaged thereby, a movable shutter in operative relation with the bolt and the recess adapted in one position to prevent such engagement, a movable catch in operative relation with the shutter adapted in its closed position to prevent movement of the shutter and restrain it in its preventive position, a spring in operative relation with the catch normally biasing it to its open position, and an electromagnet connected to the circuit in operative relation with the catch adapted when energized to hold the catch in its closed position.

In witness whereof, I have hereunto set my hand this 28th day of January, 1913.

GILBERT WRIGHT.
